MAINE.

CLOTH-GUIDING MEANS FOR LOOMS.

Application filed April 12, 1927. Serial No. 183,169.

This invention relates to cloth guiding means for the cloth as it is wound upon the cloth roll shaft by the take-up mechanism of the loom, whereby the finished roll of cloth 5 will have flat ends and the cloth be wound firm and straight.

Should the cloth as it is wound upon the cloth roll shaft by the take-up roll be deflected to one or the other side during the 10 winding operation, the selvage edges of the wound roll of cloth will not be in the same plane transversely of the cloth roll, and one of the objects of the present invention is to provide means of simple and effective character 15 for guiding the cloth as it is wound upon the cloth roll shaft to insure that the selvage edges will be superimposed one upon the other.

A further object of the present invention 20 is to provide a cloth guiding means which shall be simple in construction, readily applied to existing looms, and wherein the number of parts will be simplified and minimized and provide a resilient cloth guiding 25 means.

The novel features of the invention and new combination of parts will be more clearly understood from the following description and the accompanying drawings of one 30 good form thereof.

In the drawings:

Fig. 1 is a perspective view of front portions of a loom provided with the present invention; and

Fig. 2 is an enlarged detached detail, showing more particularly the construction of the cloth guiding means and its association with the cloth roll.

The loom frame 1 may be of usual construction and of any appropriate character, and in the present instance of the invention the front portion of the loom is provided with guides 2, a pair at each side of the loom, between which is mounted the cloth roll shaft support 3, on the top portion of which is supported the cloth roll shaft 4. As usual in looms of this general construction, the cloth roll shaft support 3 is provided with rack teeth 5 which engage pinions 6 mounted on a lower spring controlled shaft 7 for normally pressing the cloth roll shaft

4 in an upward direction and yet permitting yielding movement of the cloth roll shaft downwardly as the cloth is wound thereon during the action of the take-up 55 mechanism of the loom. The cloth roll guide constituting the present invention is herein shown with the above described character of cloth roll shaft support 3, but it is obvious that it may be associated with any 60 other usual type of support.

In accordance with the present invention, the cloth guiding means is associated with the cloth roll shaft support, and one at each side of the loom, with the result that one or 65 the other of the cloth guiding means will act upon the cloth as it is wound upon the cloth roll shaft 4 to maintain the selvage edges of the cloth in superposed relation.

The cloth roll guide comprises a body 70 member 8 which may be formed of suitable material and preferably, though not necessarily, of wood, and the cloth guiding face of the body member is plain, smooth and unobstructed, to act upon the cloth selvage. 75 The body member 8 is preferably provided with a concave portion 9 of a contour to embrace a portion of the cloth roll shaft 4, as indicated in Fig. 2.

In order to properly associate the body 80 member 8 of the cloth guiding means with the cloth roll shaft supports, a novel character of bracket means is employed which is of simple character, readily applied to looms now in use, and of resiliency to a degree sufficient to act yieldingly upon the cloth 85 selvages.

As more fully shown by Fig. 2, the body member 8 has secured thereto a bracket 10 which may be appropriately held to the body 90 member by screw bolts 11 which pass through the flat extension of the bracket and through, or partially through, the body member 8.

The bracket 10 has an outwardly deflected 95 portion 12 and is preferably formed of resilient material, such as sheet metal, and extending from the outwardly deflected portion 12 the bracket 10 is provided with a securing portion 13 which is in substantial 100 parallelism with the outer face of the body member 8 and spaced therefrom to receive a

securing bolt 14, whereby the cloth guide or body member 8 is held in position to guide the cloth selvages as the cloth is wound upon the cloth shaft 4.

As indicated more particularly in Fig. 2, the securing portion 13 of the bracket is provided with a slot 15 extending substantially parallel with the body portion 8 of the cloth guide, and, as shown, such slot 15 may be appropriately formed by a bifurcation of the securing portion 13.

The securing bolt 14 is provided with a head 16 and the spaced relation between the body member 8 and the securing portion 13 of the bracket affords ready access to the head of the bolt for turning it to secure the cloth guide to the cloth roll support 3.

The bracket as shown is preferably, though not necessarily, formed of a single piece, and its outward extension 12 is produced by bending the single piece of material outwardly and then bending the outward portion upwardly, as indicated in Fig. 2, to form the securing portion 13, which is thus in separated or spaced relation with the outer face of the body member 8. The resiliency of the outward extension 12 of the bracket provides a simple and yet effective means for yieldingly holding the cloth guide or body member 8 in operative relation with the sides of the cloth roll, and yet permits yielding movement of the cloth guides to accommodate for any slight variation in the ends of the cloth roll.

The length of the cloth guide or body member 8 should be equal to or greater than the final radius of the cloth wound upon the cloth roll shaft, in order that the cloth guide may act upon the cloth roll continuously during the winding operation.

The securing bolt 14 is preferably threaded and its threaded portion enters a recess in the top portion of the cloth roll shaft support 3, so that by manipulation of the head 16 of the bolt in the space between the body portion 8 and the securing portion 13 of the bracket, the cloth guide may be readily assembled with the cloth roll shaft support 3 without disorganizing the assembled parts in the loom.

The slotted portion 15 or bifurcated securing portion 13 affords ready means for adjustment of the cloth guide or body member 8 towards and from the cloth roll shaft 4, and such adjustment may be readily made because the bolt head 16 is readily accessible by tool for manipulating the securing bolt.

It will be apparent from the invention as hereinbefore described, that a very simple, effective and laterally yieldable cloth guide is provided for each end of the cloth as it is wound upon the cloth roll shaft whereby

the selvages of the cloth are caused to be superposed in proper relation.

What is claimed is:

1. In a loom, the combination of a cloth roll shaft, a support for the end thereof, an end guide for the cloth as it is wound upon the cloth roll shaft, a supporting bracket for the end guide having an outwardly deflected portion provided with an angular extension separated from the outer face of the cloth roll guide, and a single securing bolt passing through the extension for securing the cloth roll guide to the cloth roll shaft support. 75

2. In a loom, the combination of a cloth roll shaft, supports for the ends of the shaft, end guides for the cloth as it is wound upon the cloth roll shaft, a supporting bracket for each of the end guides having an outwardly deflected portion provided with an extension substantially at right angles to the outwardly deflected portion and spaced from the outer face of the cloth guide, and a securing bolt passing through the extension for securing the guide to the cloth roll shaft support. 80

3. In a loom, the cloth roll shaft, supports for the ends thereof, and parallel end guides to cooperate with and maintain flat the ends of the cloth wound upon the cloth roll shaft, each of said end guides comprising a flat body member, a bracket secured to the outer face of the body member and provided with an outwardly bent portion terminating in a slotted securing portion substantially parallel to the body member and spaced therefrom, and a securing bolt passing through the securing portion for securing the body member to the cloth roll shaft support. 95

4. A cloth roll guide for looms, comprising a body member, a bracket secured to the body member and having an outwardly extending resilient portion, a securing portion extending from the resilient portion parallel to the body member and spaced therefrom, and a securing bolt passing through the securing portion and having a head thereof between the securing portion and the outer surface of the body member. 100

5. A cloth roll guide for looms, comprising a body member to maintain flat the ends of the roll of cloth, a bolt for securing the body member in operative position, and a bracket secured to the body member and having an outwardly deflected portion terminating in a slotted securing portion parallel to the body member and spaced therefrom to provide a ready access to the bolt. 115

In testimony whereof, we have signed our names to this specification.

ELIAS S. MOORE.

ARTHUR L. GARNER,
